ELECTRICAL CONNECTOR

Clifton C. More, Erlton, N. J., assignor to Radio Corporation of America, a corporation of Delaware

Application May 29, 1952, Serial No. 290,730

10 Claims. (Cl. 333—6)

This invention relates to electrical connectors for making a branch connection from a main transmission line, and particularly to an electrical connector for making a branch connection from twin-wire transmission line.

The invention may be employed to advantage to connect a plurality of receiving units employing twin-wire input lines, such as television receivers and the like, to a single twin-wire transmission line, such as an antenna or like signal input source.

Transmission line branch connections of the type employed in department stores, for example, multiple operation from a single antenna lead-in of television receivers to be viewed by the public, are well known. Such networks, or branch connections, however, generally require considerable skilled labor to mount. The transmission line leads either must be soldered or otherwise fastened to respective terminals of isolating impedance elements, and care must be exercised in mounting the network to a firm support, such as a baseboard or the like. In some instances, soldering operations have been dispensed with by the provision of terminal boards, or other means, ordinarily requiring considerable equipment and also involving skilled labor for installation.

Accordingly, it is an object of this invention to provide an improved electrical connector which overcomes the above and other disadvantages.

It is another object of this invention to provide an improved electrical connector for making a branch connection of a twin-wire transmission line to another twin-wire antenna transmission line which connector is relatively simple to assemble and mount, and has no serious electrical disadvantages.

It is still another object of this invention to provide an improved transmission line tap or branch connection assembly having component parts of simple construction which are easily replaceable and economical to manufacture.

A further object of the invention is to provide a branch connector which is simple, rugged, and easily mounted to a baseboard or the like.

In accordance with a preferred embodiment of this invention, there is provided a transmission line tap assembly comprising a substantially cylindrical insulating body portion having transversely slotted ends upon which caps are threadedly mounted. Two parallel spaced bores through the body portion are provided for receiving a pair of impedance elements. Recesses or cavities are provided in the ends of the body portion both for receiving the terminal leads of the impedances to be bent into them and for securing contact thereto in a manner to be described. A pair of flat insulating inserts on one side thereof supports a pair of spaced, parallel, short conductive bars to contact the impedance leads. Each bar is connected on the other side of the insert to pronged contacts. Each threaded cap has a central protuberance, which on attachment extends toward the prongs. Thus upon a twin-wire transmission line being laid across the insert and across the contact prongs, and

2

the cap being tightened, the protuberance presses against the line, as a biasing means, thereby forcing the prongs into the line and into contact with the wires therein. The arrangement provides a connector assembly in which the correct connections are automatically obtained regardless of which connector ends the respective antenna and receiver transmission lines are secured to.

The foregoing and other objects, advantages, and novel features of the invention will be better understood from the following description with reference to the accompanying drawing, in which like reference numerals refer to like parts, and in which:

Fig. 1 is a view in perspective showing the use of electrical connectors between several branch receiver lines and one main transmission line in accordance with this invention;

Fig. 2 is an exploded view showing the parts of an electrical connector in accordance with the invention;

Fig. 3 is a view in longitudinal cross-section of the connector shown in Fig. 2;

Fig. 4 is a cross-sectional view along the line 4—4 of Fig. 3; and

Fig. 5 is a schematic diagram of the connections provided between one transmission line and two other transmission lines by connectors in accordance with this invention.

Referring particularly to Fig. 1, a plurality of branch connections from a main twin-wire transmission line 10 to parallel-line or twin-wire transmission lines 24, 36, and 38 are made by the similar connectors 12, 14, and 16, respectively. The connectors 12, 14, and 16 are similar, and only connector 12 will be described in detail. The connector 12 comprises a body portion 18, preferably substantially cylindrical in shape, provided with transverse slots 20, 22 in the opposite ends thereof. The slot 20 receives the main transmission line 10 which may be, for example, a lead-in from a television antenna (not shown). The slot 22 receives transmission line 24, which may lead to a television receiver (not shown). End caps 26 and 28 secure the respective lines 10 and 24 in place at the respective ends of the body portion 18. Through one of the caps, for example the cap 26 securing the signal conveying line 10 within the slot 20, a screw 32 may be inserted for the purpose of securely attaching the connector 12 to a suitable support, such as a baseboard 34 or the like. The shank of the screw serves as an arbor or axle upon which end cap 26 may turn in securing line 10 to connector 12 without twisting the line. In like manner, the connectors 14 and 16, similar to the connector 12 are adapted to connect respective output lines 36, 38 to the signal conveying line 10, and for attachment to baseboard 34.

Obviously other connectors could be added to the signal conveying line 10 in the same manner at any desired point along line 10 without interruption of service to those already connected, and without cutting, splicing, or soldering. The respective lengths of the signal conveying line 10 between the respective connectors 12, 14, 16 in actual practice may be much greater than appears in the drawing, for example of the order of several or many feet, and these lengths may be selected at will.

Referring particularly to Figs. 2 to 4, inclusive, which show the construction and arrangement of the various parts of the connector 12, the ends of the body portion 18 are preferably identical and symmetrical to a central plane transverse to the cylindrical body's axis. Accordingly, reference to the construction of the body portion 18, particularly at the ends thereof, will be made particularly to the upper end thereof as viewed in Figs. 2 and 3. A cavity or recess 42 is provided in the one end of the body portion 18. This recess 42 is substantially rectangular, cen-

tered on or symmetrical with the axis of the body portion 18, and oriented at right angles to the transverse slot 20. The recess 42 may be considered as including the central portion of the slot 20, or as a separate recess transverse to the slot. The body portion 18 at each end is externally threaded as indicated at 44, 46. The threaded portions have the same pitch and diameter and are centered on the slot 20 and recess 42 and coaxial with the body portion 18.

Between the recesses such as 42 the ends of body portion 18 are a pair of parallel longitudinal bores 50, 52 located on opposite sides of the axis of the body portion 18 and spaced along the center line of the transverse slot 20. The openings 50, 52 are preferably cylindrical for receiving a pair of cylindrically shaped impedance elements, such as the bodies of resistors 54, 56. The terminal leads 58, 60 and 62, 64 of the respective resistors 54, 56 extend into the recesses from the openings, as shown more clearly in Figs. 3 and 4, and are bent so as to rest against the respective transverse surfaces of the recesses in body portion 18 adjacent to the openings 50, 52. In a preferred arrangement, the respective terminal leads 58, 62 and 60, 64 in each recess, are bent diagonally toward, and with their ends in, a recessive corner of the cavity remote from the end of the resistors, with adjacent leads such as 58, 62 substantially parallel as seen more clearly in Fig. 4. Thus there is no contact between terminal leads. As is clear from the view of Fig. 4, when the respective terminal leads 58, 62 and 60, 64 in the respective recesses in the opposite ends of the body portion 18 are so arranged, the possibility of accidental contact between them due to inadvertent twisting of either resistor body is substantially eliminated. The resistor bodies are prevented from twisting or rotation by engagement of the leads in the recessive corner angles of the recesses 42, and inadvertent contact is prevented.

A substantially cross-shaped flat insulating insert member 66 supports a pair of parallel, short conductive members or bars 70, 72 exposed on one flat surface. Each end of the conductive bars extends through the insert member to terminate in double pronged contacts 31 exposed transversely to the other flat member surface. The bar ends are bent, just at or before the prongs 31, as at 33a, on the other flat surface to hold the bar and prongs in place secured to the flat insert member 66. The insert 66 is adapted to be placed in the recess 42 with the short conductive members 70, 72 facing toward the terminal leads 58, 62. A similar arrangement of flat insulating member 68 and contact bars 74, 76 is provided to fit in recess 46.

A portion of each insert 66, 68 engages respectively a short distance through the transverse slots 20, 22. The dimensions of the recesses and the slots are such that the respective inserts 66, 68 being placed therein have a sliding easy fit, and the respective short conductive bars 70, 72, and 74, 76 are on opposite sides of the center line of the transverse slot. This arrangement insures that each conductive bar will contact only one resistor terminal lead and offers two sets of prongs to contact each wire of a twin-wire line.

As previously explained, end closing caps 26 and 28 are provided for the ends of the body portion 18. Each cap is threaded internally for cooperative threaded engagement with the threaded portions 44, 46 on the respective ends of the body portion. Furthermore, the caps 26, 28 are provided with respective central protuberances or biasing means 80, 82 which extend from the interior of the respective caps 26, 28 beyond the open faces thereof. With the transmission lines 10, 24, placed in the respective transverse slots 20, 22 as shown in Figs. 1 and 3, and the caps 26, 28 mounted on the ends of the body portion, as the caps are tightened, the protuberances 80, 82 bear against the respective transmission lines 10, 24 and force them against the double pronged contacts presented thereto with sufficient pressure that the prongs penetrate the insulation of the transmission lines 10, 24 and make contact the respective leads 85, 86 and 87, 88 therein.

It is to be noted that, due to the symmetrical arrangement of the transmission line tap as above described, a reversible transmission line tap is provided, in that respective transmission lines to be coupled thereby may be placed in either end. Furthermore, if it is so desired, the mounting cap 26 can be located on the end of the body portion as desired, because the caps 26, 28 are interchangeable.

Referring particularly to Figs. 4 and 5, it is clear that the resistors cross-couple the leads of the respective parallel wire transmission lines. This is due to the particular arrangement of the resistor terminal leads and the bars and prong contacts in contact therewith as above described. Accordingly, lead 85 in the signal conveying line 10, instead of being coupled to the lead 87 of the transmission line 24 B1 directly thereunder is coupled to the lead 88 directly under the lead 86 of the signal conveying line 10.

It should be noted that the double-pronged contacts as provided adapt the tap for accommodating transmission lines having different size leads. At present, two standard types of transmission lines are employed for television antennas and receivers, and the leads in these lines are of different size and different spacing. Thus for a line having narrower spaced leads, the innermost prong contacts will puncture the line insulation and contact the respective leads. Similarly for lines having leads more widely spaced, the outermost prong contacts are aligned to engage the respective leads.

In making a branch connection with the connector, in order to affix it to a baseboard or other support, the screw 32 is first inserted in cap 26 and then screwed into the baseboard as 34 (see Fig. 1). The screw 32 is driven in only far enough to hold the cap 26 on the screw shank as an arbor in the central hole in the cap 26, but not so far that pressure of the screw head against its seat in the cap prevents rotation of the cap 26. Thereafter, the main transmission line 10 is inserted in the slot or passageway 20. Then the cap 26 is tightened on the connector body by rotation of the cap, and twisting of the lead-in line 10 is avoided. The screw may be tightened sufficiently far to afford a satisfactorily firm mounting of the connector after the cap 26 is affixed. This is an important feature, permitting easy mounting and at the same time taking advantage of the symmetrical construction of the connector.

Referring to Fig. 5, the equivalent electrical circuit resulting from typical application of the connector is shown. The resistors 54, 56 prevent too much energy being withdrawn for any single branch line such as 24. These act as isolating resistors, as known in the art. Only the branch line connections 24 and 36 are shown in Fig. 5, which is otherwise self-explanatory.

From the foregoing, it is clear that there has thus been described a novel electrical connector or transmission line tap which employs a minimum number of simple component parts, and which may be employed to couple two, twin-lead transmission lines by the simple expedient of placing the respective lines across the ends thereof and securing such lines in place with threaded caps.

60 What is claimed is:

1. An electrical connector comprising an insulating body portion, having a recess at each end thereof through each of which a twin-wire transmission line may extend, a pronged electrical contact member in each recess with a prong in registry with each of the transmission line wires to be received therein, an impedance element within said body portion coupling a pair of contact members in opposite end recesses, removable caps one for threadedly engaging each end of said body portion, each cap having bias means on the cap operable when the cap is threadedly engaged to force the transmission lines placed in said recesses against the wire registering prong, whereby said contact member prongs penetrate said transmission lines and contact with wires thereof to couple through said impedance element a pair of said wires of

different lines, one of said caps being provided with a central opening, and a mounting element located in said central opening, said mounting element having a shank and a head, the shank serving as an arbor for the cap only, whereby the connector may be readily mounted leaving the said one cap free for rotational engagement or disengagement with the body portion, without rotation of said body portion.

2. A transmission line tap for resistively coupling one insulated twin-wire transmission line to another insulated twin-wire transmission line comprising, in combination, a substantially cylindrical insulating body portion having an axis and having coaxial externally threaded end portions, substantially rectangular and identical recesses provided in said end portions, said body portion having a pair of bores parallel to said axis extending through said body portion between said recesses, a removable impedance element in each of said bores, terminal leads at the opposite ends of the impedance elements extending into the respective recesses, said leads within each recess being arranged therein parallel to each other, normal to said axis and extending from the ends of the respective impedances to remote recessive corners of the recesses, a pair of flat insulating insert members each bearing a pair of parallel conductive bars exposed on one surface thereof, each insert resting within a different recess with the pair of conductive bars on opposite sides of said axis, whereby each conductive bar contacts with one and only one terminal lead of an impedance element, each of said conductive bars terminating in double pronged contacts extending through to the other surface of said insulating inserts, and bent at the ends to retain the bars on the flat members but with the prongs normal to said other surface, a transverse slot in each end portion of the width of twin-wire transmission line to be received therein, each said slot being also transverse to the recess at its end, two internally threaded cap portions for threaded engagement with either end of said body portion, and internal protuberances provided in said cap portions as biasing means for effecting a desired pressure of the transmission lines against said prongs to effect contact of the prongs by penetration of the twin-wire lead insulation.

3. The combination defined in claim 2, in which at least one of said cap portions is provided with a central opening extending through the protuberance thereof for receiving a screw member the shank of which may thereby serve as an arbor for the cap having the opening, and whereby the tap can be mounted in a desired manner with such screw member and connected to a main transmission line without the latter being cut, spliced, or service-disrupted.

4. A connector comprising, in combination, an insulating body portion formed with recesses in the respective opposite ends thereof for receiving the respective body portions of two insulated multiconductor cables, and with a plurality of apertures therethrough equal in number to the number of conductors in one of said cables and extending from one of said ends to the other of said ends; a contact member located in each of said recesses, respectively, each said member including an insulator plate and a plurality of pointed, outwardly-extending, conductive terminal members mounted on said plate for engaging different ones of said conductors; and a pair of end caps adapted to engage the respective ends of said insulating body portion and, when said cables are in place in said recesses between said contact plates and end caps, to force said cables against said pointed terminals thereby causing said terminals to pierce the insulation of said conductors and to contact different ones of said conductors, said apertures in said insulating body portion being adapted to receive therein coupling elements for connecting the terminals of one of said contact members to the corresponding terminals of the other of said contact members.

5. A connector comprising, in combination, an insulating body portion formed with recesses in the respective opposite ends thereof for receiving the respective body portions of two insulated, twin wire transmission lines, and with two apertures therethrough extending from one of said ends to the other of said ends; a contact member located in each of said recesses, respectively, each said member including an insulator plate and at least two pointed, outwardly-extending conductive terminal members mounted on said plate for respectively engaging the twin wires of said transmission lines; and a pair of end caps adapted to engage the respective ends of said insulating body portion and, when said transmission lines are in place in said recesses between said contact plates and said end caps, to force said transmission lines against said pointed terminals thereby causing said terminals to pierce the insulation of said wires and to respectively contact said twin wires, said apertures in said body portion being adapted to receive therein coupling elements for connecting the terminals of one of said contact members to the corresponding terminals of the other of said contact members.

6. A connector comprising, in combination, an insulating body portion formed with recesses in the respective opposite ends thereof for receiving the respective body portions of two insulated multiconductor cables, and with a plurality of apertures therethrough equal in number to the number of conductors in one of said cables extending from one of said ends to the other of said ends; a contact member located in each of said recesses, respectively, each said member including an insulator plate and a plurality of pointed, outwardly-extending, conductive terminal members, at least one for each conductor of one of said cables, mounted on said plate for respectively engaging said conductors of said cable; and a pair of end caps adapted to engage the respective ends of said insulating body portion and, when said cables are in place in said recesses between said contact plates and end caps, to force said cables against said pointed terminals thereby causing said terminals to pierce the insulation of said conductors and to contact different ones of said conductors, said apertures in said body portion being adapted to receive therein coupling elements for connecting the terminals of one of said contact members to the corresponding terminals of the other of said contact members.

7. A connector as set forth in claim 6, wherein said opposite ends of said body portion are provided with threads and said pair of end caps are provided with threads which are engageable with the respective threads on said opposite ends of said body portion.

8. A connector as set forth in claim 7, and further including a resistor element located in each of said apertures respectively, for connecting the terminals on one of said contact members to the corresponding terminals on the other of said contact members, said resistor elements serving as isolating elements.

9. A connector as set forth in claim 7, wherein one of said end caps is formed with a central aperture therethrough, and further including a mounting element located in said central aperture, said mounting element serving as an arbor for said cap, whereby said connector may be mounted on a support by securing said mounting element to said support, engaging the threads of said end cap with the threads on one end of said insulating body portion, and tightening said connector by rotating said end cap about said mounting element while maintaining said body portion stationary.

10. A connector for coupling one insulated twin wire transmission line to another insulated twin wire transmission line comprising, in combination, a substantially cylindrical insulating body portion having an axis and having coaxial, externally threaded end portions, said body portion being formed with substantially rectangular identical recesses in said end portions, said body por-

tion having a pair of bores parallel to said axis extending through said body portion between said recesses, said bores being adapted to receive therein coupling elements; a pair of flat insulating insert members, each bearing a pair of parallel conductive bars exposed on one surface thereof, each insert resting within a different recess with a pair of conductive bars on opposite sides of said axis, whereby each conductive bar is in position to contact a coupling element, each of said conductive bars terminating in double pronged contacts extending through to the other surface of said insulating insert members, and bent at the ends to retain the bars on the insulating members but with said pronged contacts normal to said other surface; and two internally threaded cap portions for threaded engagement with either end of said body portions, said cap portions being formed with internal projections; whereby when said transmission lines are in

position between said double pronged contacts and said projections on said end caps, tightening said end caps onto said body portion causes said transmission lines to be forced against said contacts and said contacts to pierce the insulation of said transmission lines and to engage the respective twin wires thereof.
